(57) **CLAIM**

The ornamental design for an electric kettle, as shown and described.

DESCRIPTION

FIG. 1 is a top, right side perspective view of a first embodiment of an electric kettle showing my new design;

FIG. 2 is a front perspective view thereof;

FIG. 3 is a rear perspective view thereof;

FIG. 4 is a right side perspective view thereof;

FIG. 5 is a left side perspective view thereof;

FIG. 6 is a top perspective view thereof; and,

FIG. 7 is a bottom perspective view thereof.

FIG. 8 is a top, right side perspective view of a second embodiment of an electric kettle;

FIG. 9 is a front perspective view thereof;

FIG. 10 is a rear perspective view thereof;

FIG. 11 is a right side perspective view thereof;

FIG. 12 is a left side perspective view thereof;

FIG. 13 is a top perspective view thereof; and,

FIG. 14 is a bottom perspective view thereof.
